TEAM STANDING DISPLAY

Eva J. Bennett, 3843 Treeline Drive, Dallas, Tex. 75224

Filed Mar. 7, 1974, Ser. No. 448,831

Term of patent 14 years

Int. Cl. D11—02

U.S. Cl. D34—5 MM

FIG. 1 is a perspective view of a team standing display showing my new design;

FIG. 2 is a front elevational view of a team standing display showing a modified form of my new design; and
FIG. 3 is a sectional view taken on lines 3—3 of FIG. 2.

The back of the team standing display is plain, flat and unornamented.

I claim:

The ornamental design for a team standing display, as shown and described.
